(57) CLAIM

I claim the ornamental design for a speaker with an amplifier, as shown and described.

DESCRIPTION

FIG. 1 is a front perspective view of a speaker with an amplifier of the present invention in which a simulated wood grain pattern is depicted;

FIG. 2 is a front view thereof in which a simulated wood grain pattern is depicted;

FIG. 3 is a rear view thereof;

FIG. 4 is a first side view thereof;

FIG. 5 is a second side view thereof;

FIG. 6 is a top view thereof; and,

FIG. 7 is a bottom view thereof.

A wood grain pattern is generally claimed, and the specific wood grain pattern depicted in the figures is for illustrative purposes only.
